APPARATUS FOR OBTAINING UNIFORM SUPERHEATING TEMPERATURES WITH VARIOUS BOILER LOADS

Heinrich Vorkauf, Berlin, Germany, assignor to La Mont Corporation, New York, N. Y., a corporation of New York

Application February 24, 1937, Serial No. 127,380
In Germany February 28, 1936

4 Claims. (Cl. 122—479)

This invention relates to apparatus for obtaining uniform superheat temperatures with varying boiler loads. The invention aims particularly so to arrange the steam generator and superheater heating surfaces, preferably contacted in like manner by the heating gases, that, as the flow of the products of combustion varies with varying boiler loads, a higher heat reception by the superheater will be effected with 5 small loads than with higher loads.

In accordance with the boiler construction art and the heating art, the apparatus for carrying out the process can be constructed in various ways. It is substantially essential that the 15 steam generator and superheater surfaces be contacted in like manner; for example, that the products of combustion flow through the generator transversely to the tubes and through the superheater likewise transversely to the tubes or that they flow, in both cases, lengthwise of the 20 tubes.

In accordance with the invention, the superheater is so constructed that it possesses in its various parts a variable capacity for taking up 25 heat and it is arranged in such manner that the part of the superheater which is located in the parts of the boiler flue through which the combustion gases principally flow at smaller loading has a larger capacity for taking up heat than 30 the part of the superheater located in other parts of the boiler flue.

In a boiler having a burner operating at right angles to the gas flow and which gives a shorter flame at smaller loads than at higher loads, the 35 superheater heating surface, according to the invention, is greater in the part of the boiler flue lying adjacent to the front wall of the heating chamber than in the part next to the back wall.

When firing with several burners, the arrangement is preferably such that in the surfaces contacted by the burners remaining in operation the ratio of the superheater heating surface to 40 the generator heating surface is greater than in the other parts of the boiler flue.

If in its course through the heating chamber a reversal of the direction of the gas flow is provided, then, according to the invention, at the turning edge a relatively large superheater 45 heating surface is provided and in the outer part of the bend the generator heating surface is principally located, so that, by small loads, the products of combustion flow, under the less effective draft, principally through the superheater heating surfaces, while with bigger loads, by 50

reason of the great velocity and the greater resistance the flow will take place more through the generator heating surfaces.

Constructions according to this invention find especially advantageous application with steam 5 generators having forced circulation of the water because with these any desired arrangement of the steam generator heating surfaces and therewith also of the superheater heating surfaces is possible.

Figure 1 is a vertical section through a steam 10 generator of the forced circulation type having the present invention embodied therein;

Figure 2 is a vertical section through a steam 15 generator also of the forced circulation type but having a different arrangement of the tubes and flues, this steam generator being particularly adapted for powdered coal firing;

Figures 3 and 4 are vertical and transverse 20 sections through a marine boiler with natural circulation and having the present invention embodied therein;

Figure 5 is a vertical section through a boiler 25 of the forced circulation type having a plurality of burners, one or more of which may be cut off when it is desired to operate at low level.

Figure 1 shows a section through a steam generator with forced circulation of the water. The burner 1 blows horizontally into the fire chamber 2, the combustion gases being conducted vertically into the flue 3. The tubes 4 form the steam generator heating surfaces, and the tubes 5 the steam superheating surfaces. The illustrated greater area of superheater heating surface in the front part of the gas flue is for the 35 purpose of drawing the greater part of the products of combustion through the front part of the gas flue when the burner, by small loading, has a shorter flame. The larger superheating heating surfaces in this part and the higher combustion gas temperature at the entrance into the superheater have the result of effecting a high 40 superheating at small loads.

If, however, the burner, at small loads, works with higher air velocity or, through the flow 45 relations, a preponderating flow of the hot gas results in the back part of the gas passage, it is then advantageous so to arrange the superheater heating surfaces in this part that they take up more heat.

The step form arrangement of the superheater and generator surfaces illustrated in Figure 1 has also the advantage that, with possible later alteration of the superheating, any desired increase or diminution of the coils 6 and 7 of the 50 55

generator and superheater tubes can be brought about.

Figure 2 shows a section through a forced circulation boiler, for example, with coal dust firing. In the fire chamber 8 the flames produced from the burner 9 go vertically upward, the products of combustion passing then into the horizontal gas flue 10 and then into the downward flue 11. The steam generator tubes 12 and the superheater tubes 13 are so arranged that, with small load, the products of combustion, drawn sharply about the turn, flow principally through the superheater heating surfaces. With higher loads, on the other hand, the gases mounting vertically in the fire chamber penetrate more into the steam generator heating surfaces because of their greater velocity, while also, because of the higher resistances caused by the greater gas masses, a uniform distribution over the entire cross section is effected.

Figures 3 and 4 show sections through a marine boiler, with natural circulation, in the tube bundles 14 of which superheater heating surfaces 15 are built in. The tube bundles are so arranged that a smaller number of boiler tubes lie before the superheater in the front part than in the back part.

According to the burner relations it is desirable to arrange the superheater surface nearer to the fire chamber either at the front or at the back. If the air velocity in all burners diminishes with the loading, then it is better to bring the superheater nearer the fire chamber at the front with small loads, as shown in Fig. 4, because the flames then become shorter and are turned earlier into the tube bundle, the important thing, in the form of the invention illustrated in Figs. 3 and 4, being to so locate the superheater tubes that the average depth of the screen of generator heating surfaces traversed by the products of combustion in the direction of their flow before contacting the superheater heating surfaces will be less with the smaller boiler loads than with the larger boiler loads.

In Figure 5 still a further arrangement of the superheater according to the invention is illustrated, which is particularly suitable when, with operation at a low level, one of the burners 18, 19, 20 is cut out. If, for example, the middle burner 19 is to remain in operation, then the superheater heating surface is increased in the middle and the generator heating surface is reduced. The tubes 16 are generator tubes and the tubes 17 are superheater tubes.

The present invention is not limited to the described arrangement of superheaters in which, through natural gas movement, a stronger superheating takes place at small loading.

What is claimed as new is:

1. Means for producing uniform superheat temperatures with varying boiler loads comprising, in combination, superheater and steam generator heating surfaces so arranged in a flue that both are contacted by products of combustion in like manner and that they so supplement each other across the flue as to produce substantially uniform draft resistance throughout the cross section of the flue, said superheater and steam generator heating surfaces being also so arranged that, when with varying boiler loads there is a correspondingly varying flow of the products of combustion, the average depth of the screen of generator heating surfaces traversed by the products of combustion in the direction of their flow before contacting the superheater heating surfaces will be less with the smaller boiler loads than with the larger boiler loads.

2. Apparatus according to claim 1, in which the average depth of the superheater heating surfaces traversed by the combustion gases will be greater with the smaller boiler loads than with the larger boiler loads.

3. Means for producing uniform superheat temperatures with varying boiler loads, comprising, in combination, superheater and steam generator heating surfaces so arranged in a flue that they are both contacted by products of combustion in like manner and that they so supplement each other across the flue as to produce substantially uniform draft resistance throughout the cross section of the flue, said superheater and steam generator heating surfaces being also so arranged that, when with varying boiler loads there is a correspondingly varying flow of the products of combustion, the ratio of superheater heating surface to generator heating surface contacted by the products of combustion will increase with the smaller boiler loads.

4. Means for producing uniform superheat temperatures with varying boiler loads, comprising, in combination, superheater and steam generator heating surfaces so arranged across a flue that they together offer substantially uniform draft resistance throughout the cross section of the flue, the ratio of superheater heating surface to steam generator heating surface so varying from one side of the flue to the other that, when with varying boiler loads there is a correspondingly varying flow of the products of combustion, the ratio of superheater heating surface to generator heating surface contacted by the products of combustion will increase with the smaller boiler loads.

HEINRICH VORKAUF.
